UNITED STATES PATENT OFFICE.

HENRY SIPE, OF CLEBURNE, TEXAS.

SWINGING GATE.

SPECIFICATION forming part of Letters Patent No. 380,772, dated April 10, 1888.

Application filed January 12, 1888. Serial No. 260,540. (No model.)

To all whom it may concern:

Be it known that I, HENRY SIPE, a citizen of the United States, residing at Cleburne, in the county of Johnson and State of Texas, have 5 invented certain new and useful Improvements in Swinging Gates; and I do hereby declare the following to be a full, clear, and exact description of the invention, such as will enable others skilled in the art to which it appertains 10 to make and use the same.

My invention relates to that class of gates known as "swinging gates;" and it has for its object to simplify and improve the construction over existing patents and render easy the 15 operation of opening and closing the gate, and at the same time by its simplicity of construction reduce the cost of manufacture to a minimum.

To this end the invention consists in the 20 novel construction and arrangement of the several parts, as will be hereinafter more fully described, and specifically pointed out in the claims.

In the accompanying drawings, to which reference is had and which fully illustrate my invention, Figure 1 is a side elevation of the 25 gate in a closed position, and Fig. 2 is a view thereof in an unlatched position ready to be swung open, that portion of the gate where it is held by pins in the main front supporting post being broken away.

Similar letters of reference indicate similar parts in both figures.

A and A' represent two main supporting- 30 posts, the former of which has secured to it near its top and bottom bolts a and a', which are passed through said posts and have their rear ends screw-threaded to receive screw-threaded nuts B B, by which they are secured 35 to the posts. The forward ends of said bolts are hooked and point upwardly to receive the eyes of bolts b and b', that hinge the rear post or batten, C, of the gate to the rear main post, A, the forward batten, C', of the gate resting 40 in pins secured in the front main post, A'. The batten C has an opening or slot, e, made therein, through which is loosely passed the top bolt, b, which is somewhat longer than the lower bolt, b'. The major portion of its unhinged or 45 free end is screw-threaded to receive a nut, D, for securing and adjusting thereon the free end

of the vertical portion of an adjustable bell-crank lever, E, which shortens or lengthens the hinge b, the said vertical portion of the lever having a hole, e, therein, through which the 55 unhinged or free end of the hinge-bolt b is passed. The lower end of this bell-crank lever E has a slot, e, in it, and is projected through an opening or slot, F, in the post or batten C, (clearly shown in dotted lines in Figs. 50 1 and 2 of the drawings,) the lever being pivotally secured in the slot F by means of a pin, G, passed transversely through the slots e F in the lever E and batten C, respectively. The pin G serves as a fulcrum for lever E, and upon 55 it the slot e in the lower end of said lever E traverses back and forth and throws the rear and upper end of the gate back and forth upon the hinge-bolt b, and operates simultaneously a suitable pivoted spring and pivotally secured catch upon the gate-batten C.

Secured to the batten C upon its rear face and near the top thereof is a flat spring, H, having its free end depending downward in juxtaposition to a loosely-pivoted catch, I, pivoted as at i, the free end of the spring H holding and confining the hooked end of the catch I in the lower end of slot F in batten C. The other and longer end of the catch is straight, its point being adapted to enter a shallow recess or depression, J, in the post A. (Clearly shown in Fig. 1 of the drawings.) The front or main post, A', of the gate is provided with pins K, between which the batten C' of the gate is retained when in its normal or closed position. The batten C' has secured to its lower end a roller, L, which supports and carries the forward end of the gate when opened in full and swung around at right angles to the post. 80

From the foregoing description, when taken 90 in connection with the accompanying drawings, the operation of the gate will be obvious, but may be briefly rehearsed as follows: The operator, to open the gate, as shown in Fig. 2, has simply to depress the bell-crank lever to a 95 horizontal position. Simultaneously with that movement of the lever the slot in the lower end of it traverses its fulcrum-pin in a direction rearwardly to the gate. At the same time it imparts motion to the upper portion of the 100 rear batten, which slides gently over or upon the upper and longer hinge rearwardly until

it abuts against the hinge of the main rear post at the same time the slotted end of the lever forces the free end of the spring out of its position against the rear batten. This releases 5 the longer or straight end of the loosely-pivoted catch, which is pivotally hung below the latch from the shallow depression in the main rear supporting post, and it falls by gravity, and the forward end of the gate then consequently 10 rides over the pins in the front or main post and assumes the position shown in Fig. 2 preparatory to being swung around at right angles to allow the passage through it of pedestrians or equestrians. A reverse movement of the bell crank lever returns the gate 15 to its normal position, as shown in Fig. 1 of the drawings.

Having thus fully described my invention and explained the operation thereof, what I 20 claim as new is—

1. In a swinging gate, the combination, with

the main posts A and A', of the slotted batten C, the hinge-bolt b, and bell-crank lever E, (said bell-crank lever having a slot, e, in its lower end which traverses a pin in the slot F of the 25 batten C,) a spring, H, and gravity-catch I, all operated as described, and for the purposes set forth.

2. The combination, with the main posts A and A', the former having the shallow recess 30 j therein, of hinges a a' b b', slotted batten C, bell-crank lever E, connected with the upper hinge-bolt, b, and with a pin in the slot F in the batten C, spring H, gravity-catch I, gate, and roller, all arranged and operated substantially 35 as set forth.

In testimony whereof I affix my signature in presence of two witnesses.

HENRY SIPE.
